UNITED STATES PATENT OFFICE

2,028,280

TYPEWRITING MACHINE

George F. Handley, Glendale, N. Y., assignor to
 Royal Typewriter Company, Inc., New York,
 N. Y., a corporation of New York

Application December 29, 1934, Serial No. 759,779

6 Claims. (Cl. 197—145)

This invention relates generally to new and useful improvements in typewriting or like machines, although more particularly to means for removably mounting the platen on the carriage.

In the patent to Myers 1,496,940, June 10, 1924, there is disclosed a removable platen and a fractional line spacing mechanism for the platen which are now embodied in one of the Royal Standard machines. The left hand end 5 of the platen is detachably journaled on the associated end plate of the carriage, a line spacing ratchet wheel is rotatably mounted on said end plate, and a separable clutch is interposed between the ratchet and the platen. The right hand end of the platen is provided with an axle which is journaled in an open ended slot in the associated end plate of the carriage, and a latch of particular construction is pivotally mounted on said end plate for cooperation with an annular groove formed in the axle to thereby retain the platen in working position.

Among the several objects of my invention are to provide alining marks to facilitate the removal and repositioning of the end of the platen adjacent the ratchet wheel, and to provide a quick retractile bearing for the opposite end of the shaft which may be easily installed on the commercial carriage without the necessity of slotting the end plate or employing the latch or forming an annular groove in the platen axle, as is shown in said Myers Patent 1,496,940.

With these and other objects in view which will more fully appear, the nature of the invention will be more clearly understood by following the description, the appended claims, and the several views illustrated in the accompanying drawings.

In the drawings:—

Figure 1 is a plan view of a portion of a typewriter carriage and platen and showing the application of my invention, a portion thereof being shown in section.

Figure 2 is a plan view of the platen.

Figure 3 is a front elevation of the structure shown in Figure 1, certain of the parts being shown in section.

Figure 4 is an enlarged section taken on the line 4—4 of Figure 3.

Figure 5 is an enlarged longitudinal section showing the releasable clutch between the line space ratchet wheel and one end of the platen.

Figure 6 is an end elevation of the platen showing one of the clutch elements mounted thereon.

Figure 7 is an enlarged longitudinal section showing the opposite end of the platen and the associated retractile bearing shaft.

Figure 8 is a perspective view of the latch.

Figure 9 is a detail sectional view showing a modified form of coupling.

Referring to the accompanying drawings, I have disclosed my invention as being applied to a typewriting or like machine which includes a carriage A having right and left end plates 10 5 and 6, the latter being provided with the usual laterally extending shelf 7. Located between these end plates and rotatably supported thereon is a readily removable cylindrical platen B.

Journalized in the end plate 6 is a spindle 8 having a handwheel 9 secured thereto. This spindle is held against endwise movement. The inner end of this spindle projects inwardly between the end plates 5 and 6 and fixed on the 20 inwardly projecting end is the usual line spacing ratchet wheel 10 and a cup-shaped clutch element 11. The inner end of the spindle is provided with an inwardly extending lateral slot 12. The spindle is provided with an axial bore 13 25 and slidably mounted in this bore is a push rod 14. A stop 15 cooperates with the rod 14 through the medium of a finger-piece 16 to limit the outward movement of said rod, the rod being normally urged outwardly by a coil spring 30 17. Secured to the adjacent end of the platen B is a head 18 having an outwardly extending hollow boss 19 for receiving the inner end of the spindle 8. The boss 19 is provided with an inwardly extending radial slot 20. A clutch element 21 is supported on the boss 18 for movements toward and from the same by means of pins 22. The clutch element 21 is in the form of a disc and is provided with clutch teeth 23 on its periphery. This clutch element 21 is adapted 40 to normally engage clutch teeth 24 formed on the inner face of the cup or clutch element 11. Coil springs 25 are mounted in the platen B for cooperation with the pins 22 to normally and yieldably hold the clutch element 21 in positive 45 driving engagement with the clutch element 11 whereby the ratchet wheel 10 and the platen B will be normally coupled so that line spacing movement imparted to the ratchet wheel by the usual line spacing lever will be transmitted to 50 the platen. The clutch disc 21 is provided with a concentric opening 26 to receive the outer end of the boss 19, and a split disc 27 which is attached to the clutch disc 21 is provided with a tongue 27a which projects radially to the cen-

15

35

45

50

55

ter of said opening. This tongue 27^a normally projects through the slot 20 of the boss 19 and into the slot 12 of the spindle 8 and into position to be engaged by the inner end of the push rod 14. Upon inward movement of the push rod 14, the tongue 27^a will be engaged thereby and the clutch element or disc 21 will be moved inwardly toward the platen to thereby disconnect the clutch element and consequently disconnect the platen B from the ratchet wheel 10 whereby the platen may be freely rotated in either direction. The above construction is all disclosed in the Myers Patent 1,496,940 referred to above.

When it is desired to remove the platen, the right hand end thereof will be disconnected from the end plate 5 of the carriage, the right hand end of the platen will then be swung upwardly until the same clears the end plate 5, and the platen can be readily removed from the carriage. It has been found in practice that if the slot 12 is not located at the top of the spindle, more or less resistance is encountered in disconnecting this end of the platen. I have, therefore, provided an indicating mark or line x on the handwheel 9 and a mark or line y on the adjacent end of the platen B. These marks x, y when in longitudinal alinement will indicate to the operator that the slot 12 of the spindle 8 is in its uppermost position whereby the platen may be removed with a minimum amount of effort.

The right hand end of the platen B is removably supported on the end plate 5 of the carriage by the following means: The end plate 5 is provided with a closed opening 29 and fitted into this opening and rigidly secured to said end plate is an outwardly extending bearing 30. The adjacent end of the platen B terminates in spaced relation to the end plate 5 and rigidly attached to this end of the platen by means of a flange 31 is a bearing sleeve C having a portion 32 extending outwardly from the platen toward the end plate 5 and an inwardly extending portion 33 positioned in an axial bore 34 formed in the end of the platen. Normally positioned in the alined bearing 30 and sleeve C is a retractile bearing shaft D for the adjacent end of the platen. By retracting this bearing shaft until the inner end thereof is free from the bearing sleeve C, the adjacent end of the platen will be freed and the platen can then be readily removed. In order to normally retain the bearing shaft D in its operative position, I have provided a latch connection between the shaft and the sleeve, and associated with this latch is a manually operable means by which the latch may be disconnected from the sleeve whenever it is desired to retract the shaft for the purpose of removing the platen. To this end the shaft D is provided with an axial bore 35 which extends inwardly from the outer end thereof, and with a radial groove 36 located intermediate the ends thereof. Located in the bore 35 at a point in register with the groove 36 is a latch 37 which is pivoted at its inner end by a transverse pivot 38 whereby the outer end of the latch may be swung outwardly in a radial plane to thereby project the outer corner 39 thereof beyond the periphery of the shaft and into engagement with either of two openings 40, 40 which are formed in the outer portion 32 of the bearing sleeve C and are located at diametrically opposite points in said sleeve. A follower 41 is mounted in the bore 35 of the shaft adjacent the inner end of the latch 37 and a coil spring 42 is located in the bore 35

between the inner end thereof and said follower. This spring functions to yieldably retain the latch 37 in its normal or operative position. The inner end of the shaft D is provided with a slot 43 for receiving a locking pin 44 which is secured to the inner end of the bearing sleeve C to thereby insure the shaft D turning with the platen B. A handwheel 45 is provided with a hub 46 having an axial bore 47 for receiving the outer end of the bearing shaft D, the hub being fixed to the shaft by a set screw 48. The outer end of the shaft D is disposed in spaced relation to the inner end of the bore 47 to form a recess 49. Slidably mounted in the bore 35 of the shaft is a latch release rod 50 having a reduced outer end 51 which projects outwardly through an opening in the handwheel 45, and attached to said projecting end is a thumbpiece 52. Mounted on the reduced end 51 and located within the recess 49 is a collar 53. A coil spring 54 is located within the recess 49 between the outer end of the shaft and the collar 53. This spring functions to yieldably retain the latch release rod 50 against inward movement. The rod 50 is provided with a cone-shaped inner end 55 which normally engages a cam nose 56 formed on the outer end of the latch 37. It will, therefore, be seen that upon inward movement of the latch release rod 50, the latch 37 will be swung inwardly so as to move the corner 39 thereof out of engagement with the opening 40 of the sleeve and thereby permit the shaft D to be retracted from the platen or entirely withdrawn from the bearing 30.

From the foregoing, it will be observed that whenever it is desired to remove the platen, the handwheel 9 and the platen B are turned until the indicating marks x and y are disposed in longitudinal alinement. The latch release rod 50 is then pushed inwardly against the tension of the spring 54 to release the latch from engagement with the associated opening 40 in the sleeve 32, and while holding the latch in its released position, the shaft D may be retracted from its engagement with the platen or entirely removed from the bearing 30. The right hand end of the platen B is then swung upwardly and then bodily removed from the carriage. When it is desired to replace the platen, the mark x on the handwheel is positioned at the top of the wheel, the platen is turned to place the mark y at the top, the left hand end of the platen is then positioned on the spindle 8 and then the right hand end of the platen is lowered into proper horizontal position, after which the bearing shaft D is inserted, the latch 37 automatically setting itself in either one of the openings 40 to thereby retain the shaft D against displacement.

In the modification shown in Figure 9, I have eliminated the latch 37 and the associated operating parts, and have provided a bearing sleeve E without the openings 40. The shaft F is provided with a reduced inner end having a transverse slot 59 extending longitudinally from the inner end thereof to form resultant spring clamping arms 60, 60. The opposed inner faces of these arms are conjointly formed with a transverse seat 61 for receiving the pin 44, the diameter of the seat being substantially equal to the diameter of the pin, and the seat being located intermediate the ends of the slot. Thus when the shaft F is inserted into the sleeve E, the arms 60, 60 will engage the pin 44 and spread 75

slightly until the pin registers with the seat 61 at which time the arms will retract and frictionally retain the shaft against longitudinal movement relative to the platen.

5 I claim:—

1. In a typewriting or like machine, the combination with a typewriter carriage having end plates, one of said plates having a bearing opening therein, a platen having one end removably supported by the other side plate, a retractible bearing shaft for the opposite end of the platen mounted in said side plate opening, and a releasable latch mounted on the bearing shaft for normally coupling the shaft and platen.

15 2. In a typewriting or like machine, the combination with a typewriter carriage having end plates, one of said plates having a bearing opening therein, a platen having one end removably supported by the other side plate, a retractible bearing shaft for the opposite end of the platen mounted in said side plate opening and projecting outwardly beyond said plate, a latch mounted in the inner end of the shaft for normally coupling the shaft and platen, and manually operable means mounted in the outer end of the shaft for releasing said latch.

30 3. In a typewriting or like machine, the combination with a typewriter carriage having end plates, one of said plates having a bearing opening therein, a platen having one end removably supported by the other side plate, a bearing sleeve fixed to the opposite end of the platen and having a radial opening therein, a retractible bearing shaft for said opposite end of the platen mounted in said side plate opening and projecting into said bearing sleeve, and a releasable latch mounted in said bearing shaft and normally engaging the opening in the sleeve for coupling said shaft and platen.

35 4. In a typewriting or like machine, the combination with a typewriter carriage having end plates, one of said plates having a bearing opening therein, a platen having one end removably supported by the other side plate, a bearing sleeve fixed to the opposite end of the platen and having a radial opening therein, a retractible bearing shaft for said opposite end of the platen mounted in said side plate opening and

projecting into said bearing sleeve, a latch pivotally mounted in the inner end of the shaft, a spring for yieldably retaining the latch in engagement with the opening in the sleeve, and manually operable means mounted in the outer 5 end of the shaft for releasing said latch.

5. In a typewriting or like machine, the combination with a typewriter carriage having end plates, one of said plates having a bearing opening therein, a platen having one end removably supported by the other side plate, a bearing sleeve fixed to the opposite end of the platen and having a radial opening therein, a retractible bearing shaft for said opposite end of the platen mounted in said side plate opening and projecting into said bearing sleeve, a latch pivotally mounted in the inner end of the shaft, a spring for yieldably retaining the latch in engagement with the opening in the sleeve, a manually operable latch release push 10 rod mounted in the outer end of the shaft for longitudinal movements relative thereto, and a spring mounted in the shaft and cooperating with the rod for yieldably retaining the latter in ineffective position.

15 6. In a typewriting or like machine, the combination with a typewriter carriage having end plates, one of said plates having a bearing opening therein, a platen having one end removably supported by the other side plate, a bearing 20 sleeve fixed to the opposite end of the platen and having a radial opening therein, a retractible bearing shaft for said opposite end of the platen mounted in said side plate opening and projecting into said bearing sleeve, a latch pivotally mounted at its inner end in the inner end of the shaft, a spring for yieldably retaining the latch in engagement with the opening in the sleeve, the outer end of the latch being provided 25 with a cam nose, a manually operable latch release push rod mounted in the outer end of the shaft for longitudinal movements relative thereto, the inner end of the rod being cone shaped 30 to engage the cam of the latch, and a spring mounted in the shaft and cooperating with the rod for yieldably retaining the latter in ineffective position.

35 GEORGE F. HANDLEY.
